WILLIAM M. PALMER, OF MIDDLEBUSH, NEW JERSEY.

Letters Patent No. 74,768, dated February 25, 1868.

IMPROVEMENT IN WATER-ELEVATORS.

The Schedule referred to in these Letters Patent and making part of the same.

TO ALL WHOM IT MAY CONCERN:

Be it known that I, WILLIAM M. PALMER, of Middlebush, in the county of Somerset, and State of New Jersey, have invented a new and useful Improvement in Water-Elevators; and I do hereby declare that the following is a full, clear, and exact description of the same, reference being had to the annexed drawings, making part of this specification, in which—

Figure 1 is a perspective view.

Figure 2 is a central vertical section.

Figure 3 is a side elevation of the shifting-lever.

Figure 4, an elevation showing the device for tripping the buckets.

The same letters are employed in all the figures in the designation of parts which are identical.

My invention consists in so arranging the mechanism for operating the buckets of a water-elevator, that by turning a winch continuously in one direction, the buckets shall be alternately elevated, and, discharging their contents, descend to be refilled, as accomplished by mechanism to be hereinafter described.

The following description will enable persons skilled in the art to construct my improvement.

A A are the buckets, which move alternately up and down along the side of the frame B, which extends down the centre of the well, supporting on each side plates B', which act as ways for the slides C C, which move freely vertically along the ways B', being bent over the edge thereof on each side. From the slides C horizontal arms D project, on which the buckets A are fastened by passing the rod through round holes through lugs attached to the bottom of the buckets. The bails F are not attached to the buckets but to the rod D on each side of the bucket. The buckets are maintained in a vertical position by means of hooks K, having springs formed at their point of attachment to the bucket, pressing them outwardly. These hooks catch over the bail and hold the bucket in a vertical position until, reaching the cylinder G, the end of the hook striking against the cylinder, it is forced back and releases the bail, when the bucket will fall forward and discharge its contents in the spout. As the bucket, in descending, passes over the roller M, it will be forced into a vertical position by said roller, and the spring at the same time be pressed by the roller over the bail. The buckets may be connected by a rope, N, passing over a pulley, O, on the end of the frame B. This, however, with heavy buckets, will not be necessary in practice. The bucket would, in that case, tip on entering the water, and be filled with the same before being raised. The buckets are suspended on ropes F, which are wound around the axle G, which is turned by a winch G² continuously in one direction. The ropes are attached to different axles, placed end to end. These axles are hollow cylinders, turning on an iron shaft extending through both of them. They are connected by the following device for causing them alternately to revolve in different directions: Two plates, H¹, are attached to opposite sides of the shaft, between the cylinders, and form bearings for two oscillating-arms pivoted centrally thereto. These arms H are constructed in the form of a T. One of the stems is bifurcated, and the stem of the other passes between the points, so that by depressing one end of the arms of either, the other will be actuated towards it. A collar, G¹, is placed on the end of each cylinder, with notches cut in the inner edge, shown at G², which will engage the arms H when pressed outwardly. The arms H are actuated alternately at each end by the following means: They turn with the central shaft, and in turning strike against the head of the levers I, by which they are thrown together alternately at each end, thus disengaging them from the notches in one cylinder, and engaging them at the same time in the notches on the other. The lever I is brought into position to complete this action by the rising guide C, which encloses the lever at its pivot-end, throws it forward and in position to receive the arms H. As soon as the slide and bucket begin to descend, the lever is disengaged and falls out of the way by its own gravity, or by the force of a spring. As there are two of these levers, one on each side, the arms H will thus be caused to oscillate alternately at each end. The ropes F, after being wrapped around the cylinders G, are carried and fastened to the rollers H². The ropes are crossed, one being wound around the roller in the same way as around the cylinder, the other in the opposite direction. Thus, as one bucket ascends it draws down the other by means of the connecting-cord N, or by its weight the other bucket will fall, in practice. Thus, as one cylinder reels up the rope, the other is turned on the shaft in an opposite direction, unwinding the rope; the upper roller, being turned by the force of the descending bucket, winds up the rope from the cylinder on which it is being wound. Thus, by a continuous revolution of the winch in one

direction, the buckets alternately ascend and descend, and as each reaches the top, it discharges its contents into the trough and immediately descends. The upper roller H^2 is made in two parts, connected by a bolt, so that they may be separated to unwind a larger amount of rope, as, upon the falling of the water in the well, a longer rope becomes necessary, or *vice versa*.

By operating the rollers with the crossed ropes, instead of the gearing used in other elevators, a great economy of power is effected by diminishing the friction.

What I claim as my invention, and desire to secure by Letters Patent, is—

1. The ropes F, cylinders G, collars G^1 , roller H^2 , oscillating-levers H, and lever I, combined so as to operate substantially as set forth.

2. The bucket A, swinging on the arm D, and provided with the spring-hook K, arranged to operate substantially as set forth.

3. The arrangement of the slides C, arm D, buckets A, bail E, and hook K, substantially as set forth.

4. In combination with the cylinders G and collars G^1 , the oscillating-arms H, substantially as described.

5. In combination with the ways B' and slide C, the lever I, arranged to operate substantially in the manner and for the purpose set forth.

In testimony whereof, I have signed my name to this specification in the presence of two subscribing witnesses.

WILLIAM M. PALMER.
